Primary Examiner — Calvin E Vasant*Assistant Examiner* — Eidiol Ghigliotti Torres(74) *Attorney, Agent, or Firm* — Boudwin Intellectual Property; Daniel Boudwin(57) **CLAIM**

The ornamental design for a wireless charging air compressor, as shown and described.

DESCRIPTION

FIG. 1 is a front perspective view thereof:

FIG. 2 is a front view thereof:

FIG. 3 is a rear view thereof:

FIG. 4 is a left side view thereof:

FIG. 5 is a right side view thereof:

FIG. 6 is a top view thereof; and,

FIG. 7 is a bottom view thereof.

The broken lines depict portions of the wireless charging air compressor that form no part of the claimed design.
